UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-RIGGING FOR RAILWAY-CARS.

1,091,848.

Specification of Letters Patent. Patented Mar. 31, 1914.

Application filed May 26, 1913. Serial No. 769,795.

To all whom it may concern:

Be it known that I, GEORGE A. JOHNSON, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of high cushioning capacity.

In the drawings forming a part of this specification Figure 1 is a plan view partly in horizontal section of a draft rigging embodying my invention, and showing the parts thereof in normal position. Fig. 2 is a plan view partly in horizontal section showing the position of parts with the preliminary spring compressed. Fig. 3 is a half cross sectional view on line 3—3 of Fig. 1. Fig. 4 is a half cross section view on line 4—4 of Fig. 1. Fig. 5 is an enlarged detail showing in perspective the wedge and the friction elements at one side of the wedge.

Referring to the drawings 6, 6 represent draft members or parts of the car frame to which the draft rigging is applied, 7 the end sill, 8 the draw bar carry iron, 9 the draw bar, 10 the draft yoke, 11 the tie plate suitably secured to the draft members, preferably by the bolts 12, 12. The draft members 6, 6 are provided with stop members, preferably integral therewith, having the rear stop shoulders 13, 13, front stop shoulders 14, 14 and preliminary stop shoulders 15, 15.

16 represents the draft gear comprising a shell 17, friction elements 18, main springs 19, 19, preliminary spring 20, a preliminary spring case 21 and a preliminary spring cap 22. The shell 17 is a hollow member, preferably rectangular in shape, open at its forward end and closed at its rear end by the preferably integral plate 23. Said rear plate 23 is outwardly extended on either side of the shell to form the flanges 24, 24 adapted to engage the rear stop shoulders 13, 13. At its forward end the shell is provided with the outwardly extended flanges 25, 25, which are adapted to engage the

front stop shoulders 14, 14. In preferable construction the shell is also provided with a rearwardly extended boss 26 against which the rear end of the draft yoke is adapted to engage, and in the recess 27 of which is received the nut 28 of the connecting rod 29. The friction elements 18 are within the shell 17, and comprise a wedge 30, the outer friction blocks 31, 31 and the intermediate friction blocks 32, 32.

The wedge 30 is preferably triangular in horizontal section, and is provided with the lateral wedging faces, 33, 33, each adapted to engage an adjacent wedging face 34 of one of the intermediate friction blocks 32. 70 The intermediate friction blocks 32 are each preferably triangular in horizontal section, each having an inner wedging face 34, an outer wedging face 35 and a rear friction face 36 which engages the rear inner face of the shell. The intermediate friction blocks are transversely movable within the shell, and are each provided with a slot 37 disposed longitudinally of the shell, and of sufficient width to permit the passage of a 80 spring bolt 38 hereinafter described therethrough without limiting the transverse movement of said intermediate friction blocks in the action of the draft gear. The outer friction blocks are each preferably 85 triangular in horizontal section, and are each provided with an inner wedging face 39 adapted to frictionally engage with the adjacent face 35 of an intermediate friction block 32, and each is also provided with an outer friction face 40 adapted to frictionally engage the inner face of the adjacent side of the shell 17. Each of the outer friction blocks is provided with a longitudinal perforation 41 for the passage of a spring bolt 95 38, the head 42 of each spring bolt being preferably slightly countersunk in the forward face 43 of the outer friction block.

Each spring bolt 38 passes through an outer friction block and the adjacent intermediate friction block through the openings 41 and 37 respectively therein, and rearwardly through a perforation 45 in the rear plate of the shell, terminating a suitable distance rearwardly of the shell herein. 105 Each connecting bolt bears at its rear end a spring washer 46, each spring washer having a recess 47 in the rear face thereof to receive the nut 48 with which the rear end of the spring bolt 38 is provided. A set of 110

main springs 19 is seated between each of said spring washers and the shell, each main spring comprising preferably an outer spring 49 and an inner spring 50 nested therein.

5 The preliminary spring case preferably comprises a hollow cylinder closed at its rear end, open at its forward end and seated at its closed end against the front face of 10 the wedge 30. Within the preliminary spring case is mounted the preliminary spring 20, which comprises preferably an outer spring 51 and an inner spring 52 nested therein, the said preliminary spring being 15 forwardly seated against the spring cap 22.

The spring cap 22 comprises a plate 53 outwardly provided with a rearwardly extended flange 54, which surrounds the forward end of the preliminary spring case 21, and centrally provided in its forward face with a recess 55 to receive the head 56 of the connecting rod 29, which passes through said preliminary spring cap 22 through a perforation 57 in the rear end of the preliminary spring case, and through a perforation 58 in the wedge, and a perforation 59 in the rear end of the shell, the same being adapted to hold the parts through which it passes in 20 assembled relation. On rearward movement of the draw bar the preliminary spring cap 22 is forced rearwardly, compressing the preliminary spring 20 within the preliminary spring case 21 until the spring cap 25 guided by the flanges 54 thereof engages the forward end of the preliminary spring case, the preliminary spring case being then on continued rearward movement of the draw bar moved rearwardly, forcing the wedge 30 30 rearwardly, which in turn forces the intermediate friction blocks outwardly, the same being in frictional engagement with the wedge, the shell and the outer friction blocks. The said intermediate friction blocks in turn force the outer friction blocks 45 forwardly in longitudinal movement. The said outer friction blocks by means of the spring bolts 38 and the spring washers thereon then draw the main springs forwardly 50 into compression against the shell.

During the movement of the parts just described and occasioned by the rearward movement of the draw bar the shell is stopped against rearward movement through 55 its engagement with the rear stop shoulders 13, 13. On forward movement of the draw bar the yoke draws the shell forwardly, the preliminary spring cap being seated against and stopped by the preliminary stop shoulders 60 15, 15, and on such forward movement of the shell the preliminary spring case is drawn forwardly, compressing the preliminary spring between it and the preliminary spring cap until the preliminary spring case 65 engages said spring cap, whereupon on fur-

ther forward movement of the draw bar the wedge, friction blocks and main springs come into action in the manner in relation to each other hereinbefore described. Upon engagement between the preliminary spring case and preliminary spring cap following the compression of the spring the shell continues to move forwardly, the friction elements and main springs being in action during such movement, until the flanges 25, 25 70 of the shell 17 engage the front stop shoulders 14, thus limiting the further forward movement of the gear.

I claim:

1. In a draft gear, a shell, a wedge, transversely movable friction blocks engaging the wedge, and longitudinally movable friction blocks engaging the transversely movable friction blocks within the shell, springs seated without the shell and connected to the longitudinally movable friction blocks.

2. In a draft gear, a shell, a wedge, transversely movable friction blocks and longitudinally movable friction blocks within the shell, springs seated against the shell, spring bolts engaging said springs, the spring bolts passing through the transversely movable friction blocks and connecting with the longitudinally movable friction blocks.

3. In a draft gear, a shell, a wedge within the shell, main friction blocks arranged either side of the wedge and adapted to be spread thereby, supplemental friction blocks engaging the main friction blocks and adapted to move longitudinally of the shell, main springs seated against the shell, and bolts connecting the main springs to the supplemental friction blocks.

4. In a draft gear, a shell, a wedge within the shell, main friction blocks arranged either side of the wedge and adapted to be spread thereby, supplemental friction blocks engaging the main friction blocks and adapted to move longitudinally of the shell, main springs seated against the shell, and bolts connecting the main springs to the supplemental friction blocks, the main friction blocks being slotted for the passage of said bolts.

5. In a draft gear, a shell, a supplemental spring, a case for the same, a wedge connected with said case, main friction blocks engaging the wedge and shell, supplemental friction blocks engaging the main friction blocks and adapted to be given longitudinal movement thereby, main springs without the shell, and bolts connecting the same to the supplemental friction blocks.

6. In a draft gear, a shell, friction mechanism within the shell, a supplemental spring connected to the friction mechanism, and main springs, the friction mechanism comprising a wedge, transversely movable friction blocks and longitudinally movable friction blocks, the main springs being seated

without the friction shell and adapted to be compressed by the longitudinally movable friction blocks.

7. In a draft rigging for railway cars, a draw bar, a draft gear, stop members and means connecting the draw bar and draft gear, the stop members having main stop shoulders and supplemental spring stop shoulders, the draft gear comprising a shell friction mechanism within the shell, main springs connected to the friction mechanism, a supplemental spring and spring case, the supplemental spring being seated against the supplemental spring stop shoulders on forward movement of the draw bar, and the spring case being adapted on such movement to stop the wedge after compression of the preliminary spring.

8. In a draft gear, a shell, a wedge, main and supplemental friction blocks within the shell, main springs and spring bolts connecting the same to the supplemental friction blocks to draw the main springs into

compression on movement of the friction blocks, the supplemental friction blocks being movable longitudinally of the shell and being adapted to be actuated by the main friction blocks.

9. In a draft rigging for railway cars, a draw bar, stop members, a yoke, a shell, friction blocks and a wedge within the shell, main springs connected to the friction blocks, a spring case engaging the wedge, a supplemental spring within the spring case and a spring cap engaging the supplemental spring, the spring cap being adapted to engage stop shoulders on forward movement of the draw bar, and the spring case being adapted to engage the spring cap after the compression of the preliminary spring, and to stop the movement of the wedge.
